UNITED STATES PATENT OFFICE.

JOSEPH B. STRAUSS, OF CHICAGO, ILLINOIS.

RECONNOITERING APPARATUS.

1,349,635.

Specification of Letters Patent. Patented Aug. 17, 1920.

Application filed August 14, 1916. Serial No. 114,932.

To all whom it may concern:

Be it known that I, JOSEPH B. STRAUSS, a citizen of the United States, residing at Chicago, in the county of Cook and State 5 of Illinois, have invented a certain new and useful Improvement in Reconnoitering Apparatus, of which the following is a specification.

This invention relates to portable search-lights and has for its object to provide a new and improved device of this description. The invention is illustrated in the accompanying drawings, wherein—

Figure 1 is a side elevation showing one 15 form of device embodying the invention;

Fig. 2 is a rear view of the device shown in Fig. 1, with the lamp removed;

Fig. 3 is a view of the platform and a portion of the movable arm is seen looking 20 in the direction of the arrow on line 3—3 of Fig. 1;

Fig. 4 is a partial plan view in part section, showing the operating mechanism;

Fig. 5 is a sectional view taken on line 25 5—5 of Fig. 4.

Like numerals refer to like parts throughout the several figures.

In the construction shown, I provide two pairs of wheels 1 and 2, each pair having a 30 connecting axle, the wheels 1 acting as the front wheels, and the wheels 2 as the rear wheels. These wheels are adjustably connected together so that they may be moved relatively to vary the distance between 35 them. In the construction shown, the two sets or pairs of wheels are connected by the frame pieces 3 and 4, which are preferably fixed to the front axle and have a sliding connection with the rear axle 5. As illustrated in Fig. 2, the rear axle is provided 40 with the guides 3^a and 4^a, in which the members 3 and 4 slide. Said members may be fixed in any desired relation by means of the pins 6, which pass through holes in the 45 guides and in the members 3 and 4 and which project on opposite sides of the axle, as shown. Movable mounted on the front wheels is a movable arm 7. In the construction shown, this movable arm is rotatably mounted upon a sleeve 8 on the front axle 9. This arm carries at its outer end the desired mechanism. As herein shown, it is provided with a platform or carrying device 10 located between the branches 11 55 of the arm 7 and pivoted thereto. This platform or carrying device is provided with

means for keeping it in a substantially horizontal position during the various positions of the arm. The carrying device is connected by pins 12 with the arms 11. Connected with these pins are the pieces 13. At the other end of the arm is a similar piece 14, these pieces being connected together by the cables or flexible parts 15 and 16. The carrying device may be provided with any desired mechanism, such as a searchlight 17. The arm 7 is also connected with the rear set of wheels. As illustrated in Figs. 1 and 3, there are two connecting pieces 18 and 19, one at each side of the arm 7, the connecting pieces being pivotally connected to said arm at 20 and 21. The other ends of the connecting pieces 18 and 19 are rotatably connected with the rear axle 5. It will thus be seen that by disconnecting the members 3 and 4 from the rear axle and moving the two axles relatively, the movable arm may be lifted or lowered and may be held in any desired position by inserting the pin 6 in the proper openings in the members 3 and 4. The two sets of wheels may be moved relatively in any desired manner. In the drawings, for purposes of illustration, I have shown one method of accomplishing this. In this construction, I provide a shaft 22 (see Fig. 4) suitably mounted in position. This shaft may be operated by means of a motor or by the handle 23 and is operatively connected by pinion 24 and gear 25 with the shaft 26. The shaft 26 is operatively connected with the drums 27 and 28 in any desired manner, as by means of the sprocket chains 29 and 30 which engage sprocket wheels 31 on the shaft 26 and sprocket wheels 32 connected with the drums. The drums 27 and 28 are provided with flexible power transmitting devices 33 and 34 which may be cables wound upon the drums and which extend back and connect with the rear axle (see Fig. 5). It will thus be seen that by rotating these drums in one direction the wheels will be moved relatively toward each other to lift the arm, while by slackening up on these cables the weight of the arm will move the wheels relatively away from each other and the arm will be thereby lowered. When the arm 7 is moved the members 13 and 14 and 15 and 16 keep the platform or carrying device substantially horizontal during all the various positions of the arm. In the construction shown in Fig. 5, the members 3 and 4 are

connected with brackets 35, which are connected with the front axle and the members 14 are also connected with these brackets. The ends of the connecting pieces 18 and 19 are preferably rotatably mounted upon a sleeve 36, and connected with the ends of these connecting pieces is the support 37 which may be made up in any desired manner, as by angle irons, as shown, and to 10 which is connected a spring 38 having between its members a coil spring 39. The end of the movable arm rests upon this spring and support, as shown in Figs. 1 and 2. I prefer to provide a wood bumper piece 15 40 (see Fig. 2) connected with the platform 10 and which engages the spring as shown. The front wheels 1 may be connected with the front axle 9 by means of the pivoted spindles 41 carrying the wheels and 20 pivoted to the axle. The device may be guided in any desired manner, as by means of the members 42, connected with the spindles 41 and a connecting member 43 connected with the tongue 44, the tongue being 25 pivoted at 45 to a bracket 46 on the axle. The member 43 is provided with a slot 47 in which works a pin 48 on the tongue 44. The device may be provided with a seat 49 connected with the arm 7. By means of this 30 construction I am enabled to provide a light, substantial, portable device wherein the movable arm carrying the searchlight acts as the frame or chassis of the device, thus doing away with the heavy, cumbersome 35 parts and at the same time securing a construction which is easily and quickly operated and which is strong and durable.

I have described in detail a particular construction, but it is of course evident that 40 the parts may be varied in many particulars without departing from the spirit of my invention, and I therefore do not limit myself to the particular construction shown.

When the arm is in its down position a 45 portion of the weight of the arm is supported upon the rear or second set of wheels. It will be noted that there is means provided for removing a portion of the weight from these wheels and transferring it to the first 50 or front set of wheels. As the arm moves up the weight on the second pair of wheels is decreased and the weight on the front set of wheels increased until when the arm is in a vertical position all the weight is on 55 the front set of wheels.

I claim:

1. A portable reconnoitering device comprising two pairs of wheels, a movable arm movably connected with one pair of wheels, 60 a controlling connection between said arm and the other pair of wheels, and means for moving said pairs of wheels toward and from each other while the said arm and controlling connection are connected therewith 65 so as to raise and lower said arm.

2. A portable reconnoitering device comprising two pairs of wheels, axles for said wheels, a movable arm movably connected with one axle, a connection between said arm and the other axle, and means for moving the axles with relation to each other while the said arm and connection are connected therewith to lift and lower the arm. 70

3. A reconnoitering device comprising a pivoted arm, a support on which it is pivoted, a connection pivotally connected with said arm intermediate its ends, a second support to which said connection is pivotally connected, and means for moving said supports relatively while said arm and connection are connected therewith to raise and lower said arm. 75 80

4. A reconnoitering device comprising two pairs of wheels, an adjustable connection between said pairs of wheels, means for moving one set of wheels along said adjustable connection to vary the angular relation between said arm and connection so as to lift or lower said arm, and means for holding said wheels in any of the various 90 adjusted positions thereof. 95

5. A reconnoitering device comprising two pairs of wheels, a cross connection between the wheels of each pair, an arm pivotally mounted upon the cross connection 95 between one pair of wheels, a shock-absorbing support connected with the cross connection between the other pair of wheels upon which the arm rests when in its inoperative position. 100

6. A reconnoitering device comprising two pairs of wheels, a cross connection between the wheels of each pair, an arm pivotally mounted upon the cross connection between one pair of wheels, a shock-absorbing support connected with the cross connection between the other pair of wheels upon which the arm rests when in its inoperative position, a connection pivotally connected with said arm between its ends 110 and with the cross connection between the wheels carrying said shock absorbing support, and an operating mechanism connecting the two cross connections and adapted when moved to move the two pairs of 115 wheels relatively to raise and lower said arm, said shock absorbing support engaging said arm when lowered so as to gradually stop the movement of said connection. 120

7. A reconnoitering apparatus comprising two pairs of wheels connected together, means for moving said pairs of wheels relatively to separate them varying distances, a cross connection between each pair of wheels, an arm pivotally mounted on the 125 cross connection between one pair of wheels, a carrying device pivotally connected to the other end of said arm, said carrying device when the arm is in its lowered position supported by the cross connection between the 130

second pair of wheels so that a part of the weight of said arm is carried by said second pair of wheels, and means for moving said arm while it is connected with said 5 cross connection to remove a portion of the weight thereof from the second set of wheels and transfer it to the other set of wheels.

8. A reconnoitering apparatus comprising a pair of wheels, an arm pivotally mounted upon said pair of wheels, a second pair of wheels, a separable connection between the two pair of wheels, a portion of 10 said arm when the arm is in its down posi-

tion being supported upon said second pair of wheels, and means for moving said arm 15 about its pivotal connection to transfer a portion of the weight of said arm from said second pair of wheels to the first mentioned pair of wheels.

In testimony whereof I affix my signature 20 in the presence of two witnesses this 15th day of July, 1916.

JOSEPH B. STRAUSS.
